UNITED STATES PATENT OFFICE.

HENRY ALINDER, OF MILWAUKEE, WISCONSIN, ASSIGNOR TO ALLIS-CHAFLERS MANUFACTURING COMPANY, OF MILWAUKEE, WISCONSIN, A CORPORATION OF DELAWARE.

CASTING-MACHINE.

1,230,360.

Specification of Letters Patent. Patented June 19, 1917.

Application filed February 28, 1916. Serial No. 81,542.

To all whom it may concern:

Be it known that HENRY ALINDER, a subject of the King of Sweden, residing at Milwaukee, in the county of Milwaukee and 5 State of Wisconsin, has invented a certain new and useful Improvement in Casting-Machines, of which the following is a specification.

This invention relates to improvements in 10 the construction of casting machines and especially to devices for automatically removing the castings from the molds of such machines.

An object of the invention is to provide 15 a casting machine which is simple in construction and efficient in operation. One of the more specific objects is to provide means for automatically removing the castings from the molds of a casting machine. An 20 other object is to provide a casting machine which is entirely automatic in its operation.

It has heretofore been customary to cast 25 molten material, such as copper and iron, in machines having a plurality of movable molds, and means for feeding molten material into the molds. In these prior machines, the castings were in most instances removed from the molds by inverting the 30 molds and depending upon gravity to cause the castings to drop out. This method of removing the castings was found to be ineffective and it was then attempted to positively remove the castings by providing an opening in each of the molds, placing a 35 movable stem in the opening, and providing means for automatically moving the stem at a predetermined time in order to gradually push the casting from the mold. These ejector devices were found to be impractical 40 due to the fact that the material flowed into the crevices between the stem and the adjacent portion of the mold, causing the casting to adhere to the mold to a greater extent than without the use of an ejector.

45 With the present invention a sharp blow is delivered against each mold after the same has been filled with metal and tilted, this blow serving to effectively release the casting from the mold.

50 A clear conception of an embodiment of the invention may be had by referring to the drawing accompanying and forming a part of this specification in which like ref-

erence characters designate the same or similar parts in the various views. 55

Figure 1 is a transverse vertical section through a fragment of a casting machine having the invention applied thereto.

Fig. 2 is a top view of a fragment of a casting machine having the invention applied thereto. 60

Fig. 3 is a diagrammatic side elevation of an automatic casting machine.

The casting machine comprises essentially a series of molds 1, an endless conveyer or 65 chain 2, conveyer guiding and actuating sprockets 5, and means for feeding molten metal into the molds 1, this means being disclosed as a ladle 3, see Fig. 3. The molds 1 are secured to the links of the chain 2 and are movable in a clockwise direction as 70 viewed in these figures, by means of the sprockets 5. The chain 2 carries anti-friction rollers 19 which engage the sprockets 5 at the ends of the machine, and the guiding rails 18 at intermediate portions thereof. The front sprocket 5 adjacent the ladle 3 is rotatably supported by means of a shaft 20 mounted in suitable bearings on the main frame 10. The rear sprocket 5 at the opposite end of the machine is rotatably supported by means of the driving shaft 11 mounted in suitable bearings 21 on the main 75 frame 10.

The gear 6 is secured to the driving shaft 85 11 and meshes with a pinion 7 secured to the cam shaft 8. The cam shaft 8 is mounted in bearings 22 supported by the frame 10 and carries a cam 9 at a portion thereof intermediate the bearings 22. When the 90 driving shaft 11 is rotated in a clockwise direction as viewed in Fig. 1, the pinion 7 and cam 9 are rotated in an anticlockwise direction. The ears of the cam 9, as disclosed, are two in number and are intermittently engageable with the tappet 14 carried by the stamp rod 13. The stamp rod 13 is slidably mounted in a front bearing 12 and a rear adjustable bearing 16 mounted upon the frame 10. The rear bearing 16 95 is adjustable relatively to the frame 10 and besides serving as a bearing for the rod 13, provides an adjustable seat for one end of the helical compression spring 15. The opposite end of the spring 15 engages a stop 100 plate 23 adjacent the tappet 14. The stop 105

plate 23 is engageable with stops 24 secured to the frame 10, to limit the travel of the plate. The bearing 16 may be locked in adjusted position relatively to the frame 10 by means of a locking set screw 17. The stamp rod 13 is mounted in a substantially horizontal position and the driving relation between the gear 6 and pinion 7 is such that the ears of the cam 9 will become effective in moving the rod 13 in a direction toward the ladle 3 at equal intervals. The molds 1 are provided with projecting bosses 4 so located and timed that a boss 4 will be brought into axial alinement with the rod 13 each time an ear of the cam 9 releases the tappet 14. When an ear of the cam 9 releases or passes out of engagement with the tappet 14, the spring 15 which has been previously compressed by the cam ear, is suddenly released and becomes effective in moving the rod 13 rapidly forward. As the rod 13 is projected toward the adjacent mold 1, it delivers a sharp blow against the boss 4. During normal operation of the machine, the molds 1 are successively moved past the ladle 3 by means of the endless conveyer or chain 2. The molten material is fed into the molds 1 at the ladle and cools as the molds advance toward the rear end of the machine. When the filled molds reach the rear sprocket 5, they are automatically tilted. While the molds are in tilted position, the stamp rod 13 delivers a blow against the boss 4 of each mold and effectively discharges the casting therefrom.

It will be noted that by properly designing the driving mechanisms for the cam 9, and maintaining a phase relation between the cam 9 and the chain driving sprocket 5, the movement of the rod 13 can be timed to automatically deliver blows against the bosses 4 while the molds are disposed substantially vertically. The molten material may be continuously fed to the molds 1 from the ladle 3, and due to the length of the machine, will have sufficiently set by the time it reaches the opposite end of the machine, to permit removal of the castings. While the device is especially applicable to machines for casting molten metal, such as copper and iron, the same may be applied to the casting of other materials.

It should be understood that it is not desired to be limited to the exact details of

construction shown and described, for obvious modifications will occur to a person skilled in the art.

It is claimed and desired to secure by Letters Patent,—

1. In combination, a mold having a casting discharge opening, means for feeding molten material into said mold, and means for delivering a blow against said mold, said blow-delivering means being located remote from said discharge opening. 60

2. In combination, a mold having an inlet and discharge opening, means for feeding molten material into said mold through said opening, and means for delivering a blow against a portion of said mold remote from 70 said opening.

3. In combination, a mold having a discharge opening, means for feeding molten material into said mold, and means for delivering a blow against said mold on the 75 side thereof opposite said discharge opening.

4. In combination, a mold, means for feeding molten material into said mold, mechanism for tilting said mold, and means 80 for delivering a blow against said mold substantially above the mid portion thereof when in tilted position, whereby an upper portion of said material is freed to swing by gravity away from said mold when the 85 same is further tilted.

5. In combination, a mold, means for feeding molten material into said mold, carrying mechanism for said mold, and means for delivering a blow against said mold in a direction away from said mechanism. 90

6. In combination, a mold, means for feeding molten material into said mold, a sprocket for changing the angular position of said mold, bearings for said sprocket, and 95 means for delivering a blow against said mold in a direction away from said sprocket bearings.

7. In combination, a mold having a discharge opening, means for feeding molten 100 material into said mold, and means for delivering a blow against said mold substantially above the mid portion thereof and substantially in the direction of discharge of material from said mold.

In testimony whereof, the signature of the inventor is affixed hereto.

HENRY ALINDER.
